UNITED STATES PATENT OFFICE.

ARTHUR WELLS ROBINSON, OF UPPER MELBOURNE, QUEBEC, CANADA.

CLAMSHELL DREDGE.

Application filed February 19, 1924. Serial No. 693,740.

To all whom it may concern:

Be it known that I, ARTHUR WELLS ROBINSON, a citizen of the Dominion of Canada, and a resident of Upper Melbourne, county 5 of Richmond, Province of Quebec, Dominion of Canada, have invented certain new and useful Improvements in Clamshell Dredges, of which the following is a specification, reference being had to the accompanying 10 drawings.

This invention pertains to that class of dredge, in which a grab or clamshell bucket is employed. The bucket is caused to drop in an open position on the surface to be 15 excavated, then close and lift, the material is deposited to one side, either on the land or into a barge. The invention relates more particularly to the means for hoisting and lowering the bucket and of revolving or 20 swinging it for the purpose of deposit. Also for opening and closing the bucket.

The ordinary and well known method of raising and lowering the clamshell bucket, is by means of suitable hoisting tackle attached to the boom of a crane or derrick. 25 The bucket is freely suspended from the end of such boom, and a swinging or slewing motion imparted to the boom, so that the bucket may deposit its load in the required place. This method is subject to several 30 disabilities, among which may be mentioned the tendency of the bucket to cant or topple over when it strikes the bottom, owing to the fact that it is suspended by a flexible hoisting 35 tackle. This is especially noticeable when the bottom is uneven, as is nearly always the case.

It is also always difficult to cause the bucket to land in the proper spot when 40 dangling freely on a long tackle from the end of the boom. Furthermore all such apparatus is necessarily unbalanced, so that the energy expended in hoisting the dead load of the bucket and its parts is wasted 45 on each lift, and the only useful work done, is that of lifting the dredged material. Furthermore the energy thus expended in hoisting the bucket, is not only wasted, but reappears in causing considerable wear of 50 the brake bands and other arrangements that are necessary for its control when lowering.

In my invention I do not employ the usual 55 apparatus, but substitute therefor a rolling cantilever boom, having perfect balance of parts, and to the end of which the clamshell bucket is connected preferably by a rigid

member, so that it can not only be raised or lowered but also pushed into or against the bottom for excavating purposes when lowered. 60

From this construction a number of advantages result, some of which are as follows:

(1) A positive thrust for digging penetration of the bucket, so that harder material 65 can be excavated than would otherwise be possible.

(2) Balance of the parts, so that little if any lost work is expended in lifting the dead load of the bucket. 70

(3) Balanced also for revolving load, so that the hull of the dredge does not list or roll, when the boom and bucket swings to one side.

(4) Boom balanced in mid-position, so 75 that the power applied to raise or lower it is stored up and used to start the return stroke.

(5) There is regenerative momentum of the boom, which saves power and increases 80 speed.

(6) Reduction of friction over all other apparatus, as the friction for both oscillating the boom and revolving it, is rolling not 85 sliding friction.

(7) Direct application of power for rolling the boom by means of cylinder and piston. No engines, shafts, gears or clutches being employed.

(8) Position of the main cylinder and 90 parts, at the rear of the apparatus, so that it acts as counterweight.

(9) Clamshell bucket of improved design, having no sheaves or shafts, and working parts projecting into the mud. Ample room 95 for mud to pile up.

(10) Direct power closing cylinder for bucket, which opens by gravity.

(11) Bucket cannot twist or topple over as when dangling by ordinary hoist. 100

(12) Ease of operation, 3 levers only required, 1 rolling, 1 closing and dumping, and one swinging.

(13) Economy of fuel.

(14) Few working parts consequently 105 less cost of maintenance.

Certain elementary forms in which my invention may be embodied, are shown in the accompanying drawings. They are however, by no means the only constructions 110 which may be adopted.

In the drawings Fig. 1 is a side elevation

of one form of a complete dredge. Fig. 2 is a plan of the same. Fig. 3 is an end view, in which the boom with its rolling platform is shown in section. Fig. 4 is a side view of 5 the clamshell bucket attached to the boom in an open position. Fig. 5 is a front view of one form of clamshell bucket attached to the end of the boom. Fig. 6 is a side view of the bucket somewhat enlarged. Fig. 7 is 10 plan of the same, and Fig. 8 is a front view of the same. Fig. 9 is a detail section view of the track and coacting parts.

In the drawings, 1 represents the scow or 15 float, 2 represents the cantilever boom, or rolling member. This rolling member is composed of two steel girders of curved form, which may be either solid plate girders or open lattice work or a combination of both. 3 is a counterweight at the 20 rear end of the boom, which may consist of one or more solid blocks of cast iron attached to the boom in any suitable manner, and sufficient to balance the parts in mid-position. This counterweight is preferably 25 bifurcated, being made in two parts as shown, each part attached to one of the girders of the cantilever with sufficient space between to clear the cylinder 15.

The under sides or tread of the girders 30 in the central part of the boom, forms an arc of a circle as at 5. The curved portion of the boom where it rolls upon the base is formed of great strength, and with a flange 6 on each side similar to the tire of a locomotive drivingwheel, so that it can roll on a corresponding horizontal steel track 7. In order to prevent horizontal displacement of the rolling portion a portion of the track 7 and the tread 5 is formed with 35 teeth or cogs 8 which engage with each other after the manner of a rack and pinion. 9 is a circular revolving platform across the top of which the two steel tracks 40 are laid upon which the girders may roll. 10 is an annular roller bearing interposed between the revolving platform 9 and the hull of the vessel. This roller bearing consists of a series of rollers 11 retained in place by a ring 12, and provided with a 45 circular track both on the under side of the platform and on the deck of the dredge.

The usual center pivot or bearing not shown is provided to prevent horizontal displacement, and this part of the apparatus 50 is or may be similar in principle and construction to that used in railway turn-tables, revolving bridges, revolving steam shovels, draglines and the like.

Rotary motion is imparted to the platform 55 9 by means of a wire rope swinging gear attached thereto, consisting of reversible winding engines 13, and the guide sheaves 14. The construction of which is or may be similar to that employed in swinging or 60 slewing the booms of dredges and derricks.

15 is the boom actuating cylinder with piston 16 and piston rod 17 mounted upon and attached to the revolving platform 9 by means of two plate girders 18. These girders are preferably of inclined form, to 70 carry the cylinder in preferred position. The piston rod 17 of the cylinder terminates in a crosshead 19 which is attached to a wrist pin 20 secured to the girders 2-2 of the cantilever boom, and the position of 75 which is preferably exactly in the center of the flange or arc on which the boom rolls. It is manifest therefore that as the rolling action takes place this wrist-pin will travel in a horizontal line, which is also the center 80 line of the cylinder and piston, and that therefore no guides or connecting rods are necessary. 21-21 are the two leaves or shells of a clamshell bucket, which may be of any preferred or usual construction. The 85 shells are connected to a head 22, by four connecting links 23. The head 22 is attached to the end of a rigid member 24, by which the whole apparatus is suspended from the end of the boom. 90

The connection to the end of the boom, is by means of two pins 25 and 26, at right angles to one another with a yoke between them, as shown in Fig. 5, so that perfect freedom of motion is secured and the bucket 95 may swing as a pendulum, either sideways or fore and aft while at the same time preserving the necessary rigidity for forcing it into the material to be excavated.

27 is a member sliding telescopically within the member 24. Its purpose is to maintain the shells 21-21 in position, and to provide an attachment for the closing rope 28, which is attached to the upper end. The 100 members 24 and 27 may be tubular, or in the 105 form of hollow box girders, or any other preferred construction, so long as one can slide within or upon the other.

At the upper end of the member 24 is a sheave 29 over which a rope or chain 28 for closing the bucket by power is made to pass. This closing rope or chain is carried within the boom to a cylinder 31, which is firmly fixed in suitable position and moves with the boom. This cylinder is single acting only, its function being to pull upon the rope 28, thereby raising the member 27 after the bucket is in contact with the ground, and causing the shells 21-21 to close powerfully and gather up a load of material within them, while the thrust or pressure of the apparatus is exerted to cause the cutting edges of the bucket to penetrate the ground through the medium of the links 110 23 and the rigid member 24. 115

It is apparent that when the bucket is lifted with its load to the high position shown by dotted lines, and upon releasing the tension of the closing rope of cylinder 120 31, the weight of the apparatus and the 125

weight of the material within the bucket will cause it to open by gravity, and dump the load, as is the usual operation of the clamshell buckets operated on the two line principle. It will be seen however, that my system of applying closing power to the bucket is essentially different from that usually employed because no multiplying sheaves, or closing wheels or gearing are employed within the bucket. There are many forms of such closing gear in use, and they are necessary as long as the bucket is suspended by a flexible tackle. But they are entirely eliminated by the use of my invention.

The centre of gravity of the rolling cantilever is preferably fixed at a point below the wrist-pin 20, for an important reason about to be described. If the center of gravity of the whole rolling apparatus were fixed to coincide with the wrist-pin 20, it would be in equilibrium in any and all positions to which it may roll upon the track. The center of gravity, however being below this point causes it to balance only in mid-position and to exert a righting moment both above and below the mid-position, the action being similar to that of a rocking chair upon the floor.

The hull is moored in place, either by spuds or mooring lines and anchorages, or both in any usual or preferred way.

The machine is controlled by suitable valves and coacting parts which admit steam or compressed air to and from the cylinders, and the control levers for the operator will or may be arranged in convenient position upon the turntable. Either steam or compressed air may be used as preferred, and the supply pipes may be carried up through the center of the turntable with any preferred arrangement of swivel or flexible joints.

Having thus described the construction of the machine, the action is now clear. Upon the admission of steam or air to the cylinder 15, the clamshell bucket is pressed down in an open position on the ground, to be excavated, and air is then admitted to cylinder 31 whereupon the closing action takes place and the bucket is filled. Immediately thereafter the pressure from cylinder 15 being relieved, the bucket begins to rise of its own accord, due to the righting moment and the energy which has been stored up in the apparatus during the down stroke. All that the cylinder 15 has to do therefore is to accelerate and control the stroke, carrying it past the neutral or mid-position, partly by means of its momentum, and partly by the additional energy imparted to it until the proper height is reached. During the lifting operation, the slewing or revolving of the boom has been put into effect, so that by the time it has reached

the top it is in proper position to dump the load, the pressure on cylinder 31 is then released, and the bucket opens by gravity, and dumps the load upon which the slewing and descending motion is recommenced.

It will be seen therefore that the power applied to the apparatus is comparatively small, and that great economy thereby results.

I am aware that the construction of a clamshell bucket and its essential parts, is old and well known, and I do not confine myself to the construction shown as the bucket may be bi-valve or tri-valve or any other preferred form. But the method of application of the closing power as described is a new and useful improvement.

Also I am aware that the principle of a rolling cantilever is old and has been used in other applications, as in bascule bridges and the like. But the application of a rolling cantilever upon a revolving platform as stated, and with the described coacting mechanism constructed and arranged for the purpose described is a new and useful improvement in dredges of the class stated. Also the turntable mounted on a live roller ring is a well known device, and has many useful applications. I do not therefore broadly claim these details or elements as heretofore used.

It will be obvious to those who are familiar with such matters that modifications other than those illustrated and described may be adopted, and yet the essentials of the invention be retained. I therefore do not limit myself to such details. There are many minor and supplemental devices connected with this operation which may be beneficially used, as for instance, a brake or attachment for holding the boom in any position.

I claim:

1. In a dredge, a balanced boom member having a rolling surface on its lower side formed in an arc of a circle and having the center of gravity located below the center of said arc so that the boom member is in equilibrium when in mid-position.

2. In a dredge, a balanced rolling boom member having a convex rolling surface on its lower side formed in an arc of a circle and having the center of gravity below the center of said arc so that the boom member is in equilibrium when in mid-position, teeth on said rolling surface and a track with teeth adapted to engage the teeth on said boom.

3. In a dredge, a normally balanced rolling cantilever boom having a convex rolling surface in an arc of a circle, a wrist pin connection at the center of the arc which moves in a horizontal line and power devices connected to said wrist pin.

4. In a dredge, a normally balanced rolling cantilever boom having a convex rolling

surface in an arc of a circle, a track for said rolling surface, a counterweight at the inner end of said boom and a portion at the outer end curved to extend below the track when the parts are in normally balanced position.

5. In a dredge, a normally balanced rolling cantilever boom having convex toothed rolling surfaces, a track for the rolling surfaces, a clamshell bucket attached to the 10 outer end of the boom, and means to actuate the boom.

6. In a dredge, a balanced rolling cantilever boom having a convex rolling surface in an arc of a circle, a wrist pin at the center 15 of the arc of the rolling cantilever boom which moves in a horizontal line, a direct acting cylinder and a piston rod in said cylinder directly attached to the wrist pin.

7. A balanced rolling cantilever boom hav-

ing convex rolling surfaces in the arc of a circle, a track for the rolling surfaces, and means to actuate the boom supported on and moved with it, the center of gravity of the boom lying substantially directly below the center of the arc of the circle when the parts 25 are in normal mid-position whereby the boom tends to return to this position when moved away therefrom in either direction.

8. A rocking cantilever boom having convex rolling surfaces on an arc of a circle and 30 having a shifting point of support beneath and on both sides of the center of gravity of said boom, a track for the rolling surfaces, a revolving turntable under said track, and means for imparting rolling movement to 35 said boom and turntable.

ARTHUR WELLS ROBINSON.
